UNITED STATES PATENT OFFICE.

JUDSON H. BOUGHTON, OF ST. LOUIS, MISSOURI.

CURTAIN.

1,161,444.

Specification of Letters Patent. Patented Nov. 23, 1915.

Application filed January 9, 1914. Serial No. 811,166.

To all whom it may concern:

Be it known that I, JUDSON H. BOUGHTON, a citizen of the United States of America, resident of the city of St. Louis and State of Missouri, have invented certain new and useful Improvements in Curtains, of which the following is a full, clear, and exact description, reference being had to the accompanying drawing, forming a part 16 of this specification.

My invention relates to a shield or curtain adapted to be applied to the radiator of an automobile for the purpose of shielding said radiator to prevent an excessive 15 cooling of the water in the radiator.

One of the objects of the invention is to produce a shield which may be adjusted along the face of the radiator to vary the 20 area of radiator surface exposed to the cooling action of the cold air currents.

Another object of the invention is to provide a radiator shield which may be adjusted upwardly from the bottom of the radiator, thereby, providing an adjustable 25 closure adapted to close the lower portion of the radiator while the upper portion of the radiator is open to permit the circulation of air therethrough. This is an important feature for the reason that the hot 30 water usually enters the upper portion of the radiator and is gradually cooled as it flows downwardly, and in extremely cold weather the radiator may be maintained at a substantially uniform temperature by 35 shielding the lower portion of the radiator.

The invention also includes certain details of construction forming part of an adjustable curtain structure, the preferred form 40 of which comprises a curtain wound around a roller and securely held so that the roller may be shifted to unwind the curtain. A flexible strand serving as a support for the roller is wound around the roller in a direction opposite to the winding of the curtain, 45 and when the roller is rotated to unwind the curtain, the flexible strand is wound onto the roller.

Figure I is a front elevation of an automobile radiator, showing my shield applied 50 thereto. Fig. II is an enlarged side elevation of the radiator, partly broken away, some of the parts being shown in section. Fig. III is a detail view showing the parts at the middle portion of the roller.

55 In the accompanying drawings: A designates an automobile hood and B is a radi-

ator provided with a filling nozzle C. A shield D comprises two curtain sections 1 wound around a roller 2, the lower ends of said curtain sections being secured to a 60 transverse bar 3. 4 designates flexible clips for securing the lower ends of the curtain sections to the lower portion of the radiator. These clips straddle the bar 3 and extend through the radiator, the inner ends of said 65 clips being bent as seen in Fig. II.

A flexible strand 5 is secured to the roller at 6 and wound around said roller in a direction opposite to the winding of the curtain sections. This flexible strand 5 is preferably a wire secured between the curtain sections and having its upper end secured to an elastic member 7 looped over the filling nozzle C. The elastic member 7 is preferably a rubber loop provided with a fabric 75 covering.

The curtain sections and the flexible strand 5 are held under tension by the elastic member 7, therefore the shield is firmly held against the face of the radiator and 80 the roller may be rotated with the result of winding up the flexible strand and unwinding the curtain sections. When the roller is so rotated it is shifted to different elevations above the bottom of the radiator and 85 it is supported at all times by the flexible strand 5.

The roller tends to drop by gravity, however, the parts are so arranged that the roller will remain in its adjusted position until it is turned by the operator. A downward movement of the roller is resisted by the flexible strand 5 which is preferably a wire arranged to unwind from the roller when the latter moves downwardly. It will 95 be noted that the roller cannot drop without bending the wire strand 5, at the same time winding the curtain onto the roller, and the energy required to effect these winding and unwinding operations is greater than 100 the force of gravity tending to move the roller downwardly. Therefore the roller is retained in its adjusted position without the use of fastening devices such as have been heretofore employed to support curtains and 105 curtain rollers.

* If desired, the upper end of the curtain and the roller may be supported by pegs or arms 8 secured to the radiator, see Fig. II.

110 I claim:

1. In a device of the character described,

- a support, a roller, a double curtain comprising a pair of curtain sections, one end of each curtain section being attached to said support and the opposite end of each curtain section being wound around the roller, and a wire having one end secured to the roller and wound thereabout in a direction opposed to that in which the curtain is wound, the other end of the wire being secured to the support at a point opposite the attachment of the curtain.
2. In a device of the character described, a support, a roller, a double curtain comprising a pair of curtain sections, one end of each curtain section being attached to said support and the opposite end of each curtain section being wound around the roller, and a wire having one end secured to the middle portion of the roller at a point between the curtain sections and wound around the roller in a direction opposed to that in which the curtain is wound, the other end of

the wire being secured to the support at a point opposite the attachment of the curtain.

25

3. In a device of the character described, a support, a roller, a double curtain comprising a pair of curtain sections, one end of each section being attached to said support, and the opposite end of each curtain section being wound around the roller, a wire having one end secured to the roller and wound thereabout in a direction opposed to that in which the curtain is wound, and an elastic compensating member connecting the other end of said wire to said support at a point opposite the attachment of the curtain so as to place the curtain and wire under tension.
